UNITED STATES PATENT OFFICE

90,952

DESIGN FOR A TIMING DEVICE

Hugh McDowell, Jr., Hollywood, Calif.

Application July 17, 1933. Serial No. 48,730

Term of patent 14 years

To the Commissioner of Patents:

I, HUGH McDOWELL, JR., a citizen of the United States, residing at Hollywood, in the County of Los Angeles and State of California, have invented a new, original, and ornamental Design for Timing Device, of which the following is a specification, reference being had to the accompanying drawing, forming a part thereof.

Fig. 1 is a plan view of the timing device of the design;

Fig. 2 is a side elevation thereof;

Fig. 3 is an end elevation of the design.

I claim:

The ornamental design for a timing device, as shown.

HUGH McDOWELL, JR.
